UNITED STATES PATENT OFFICE.

ABRAHAM KIPP, JR., AND HUGH MURPHY, OF SING SING, NEW YORK.

FLUID-PRESSURE REGULATOR.

SPECIFICATION forming part of Letters Patent No. 224,190, dated February 3, 1880.

Application filed November 16, 1879.

To all whom it may concern:

Be it known that we, ABRAHAM KIPP, Jr., and HUGH MURPHY, of Sing Sing, Westchester county, State of New York, have invented 5 Improvements in Gas-Regulators, of which the following is a specification.

Our invention consists in certain improvements in fluid-pressure regulators for regulating automatically the pressure of gas, designed 10 for the purpose of increasing their efficiency, adding to their safety from accidental explosion, of obviating their liability of getting out of order, and of conducing to facility in their construction.

15 The drawing, Figure 1, is a perspective sectional view of a self-acting regulator, in which—

20 A indicates the passage leading from the gas-holder; B, the globular chamber containing the valve, and C the opening connecting with the mains. A neck, D, connects the globe B with the flattened circular chamber E, in which is a diaphragm, F, formed of two thin metallic plates, holding between 25 them a larger disk of leather or other flexible gas-tight material, the extended margin of which is held between the flange of the lower part of the chamber E and the ring G by screws. The cap forming the upper portion 30 of the chamber E is attached to the ring G by other screws, so that it can be removed, if necessary, without disturbing the fastenings of the diaphragm.

35 A casting, H, separate from the globe B, to which it is attached by bolts through its flange, forms the double valve-seat for the valve I. The latter is in one casting, together with its hollow stem and the feathers J, which guide its motion vertically. Only one of the feathers 40 is shown in the drawing.

45 The valve-rod K, connected with the valve, as hereinafter described, passes upward through the neck D, and is connected with the center of the diaphragm F, above which the rod is prolonged through the cover of the chamber E, and is on the outside jointed, by means of a chain, L, to the balanced lever M, having on its outer arm the adjustable weight N, by which the regulator is set to act at the pressure desired.

50 The action of the regulator is as follows:

The weight on the lever having been set for the desired pressure, the gas which has passed the valve I, if of a pressure in excess of that desired, will act on the under side of the diaphragm F, causing it to rise, together with the valve I suspended below it, thus closing the valve-openings until the pressure is suitably reduced. On the other hand, when the pressure is deficient in the main the diaphragm and valve descend until the openings are just wide enough to allow the proper amount of gas to pass, the valve being thus automatic at any pressure at which it may be set to act.

55 Experience in the manufacture and use of regulators such as above described and others of like nature have pointed out the necessity of improvements in some of the details, which improvements constitute parts of our invention. In the movement of the diaphragm there 60 is apt to be a slight divergence from the exact central line, caused by unequal degrees of rigidity in the material used for the flexible parts of the same, giving rise to objectionable friction of the valve or the edges of its feather-guides against the seat-openings. In an instrument so delicate, required to act at such 65 extremely slight variations of pressure, it becomes essential to relieve the valve from any lateral pressure which might be communicated through the rod. To obviate the difficulty referred to, the stem connecting the two disks of the valve I is bored of a larger caliber than the size of the valve-rod K, or is cast 70 with a conical hole, except at the lower extremity, where it is contracted so as just to 75 easily fit the valve-rod.

75 The rod K has a head or knob on its lower end, which fits in cavities or is otherwise confined between the bottom of the valve I and the cap O, forming a universal joint, which leaves the rod at liberty to diverge slightly 80 from the perpendicular without affecting the action of the valve. The cap O is perforated 85 to allow any moisture which may condense in the bore of the stem to pass out.

90 At the point where the valve-rod K passes out through the cover of the diaphragm-chamber E to connect with the balanced lever M it is essential that no gas escape into the 95 apartment containing the apparatus in case of any leakage or rupture occurring in the dia-

phragm, which might endanger explosion if unobserved in time, several disastrous explosions having been known to occur from this cause. For the purpose of avoiding this danger we employ a mercurial seal formed by a deep annular channel, P, cut in the cylindrical neck of the cap of the diaphragm-chamber E, which channel is filled with mercury. Affixed to the rod K is the cylindrical bell Q, made to fit loosely into the channel P, with its edge submerged in the mercury, thereby constituting a gas-tight seal, allowing a frictionless up-and-down motion to the rod, and permitting a slight lateral divergence of the same for the purpose before alluded to. From above the diaphragm a small pipe, R, makes a communication with the outside air, and conveys to a place of safety the gas, if any, which may leak through the diaphragm.

We claim as our invention—

1. In combination with the diaphragm F, consisting of the flexible disk and plates, the valve I, having the conical opening through its center, and the rod K, the latter being connected to the lower part of the valve by a ball-joint, substantially as shown and described. 26
2. The mercurial seal, in combination with the valve-rod K, chain L, counterbalance-lever M, pipe R, and diaphragm-chamber E, substantially as shown, and for the purpose de- 25 30 scribed.

A. KIPP, JR.
HUGH MURPHY.
